Primary Examiner — Marianne N Pandozzi

(57) **CLAIM**

The ornamental design for a beverage container identification marker kit, as shown and described.

DESCRIPTION

FIG. 1 is a front elevation view of a beverage container identification marker kit showing my new design with a plurality of decals and a plurality of wristbands separated for clarity;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is an isometric view thereof.
